CLAIM

The ornamental design for a display screen with transitional graphical user interface for the management of wine storage, as shown and described.

DESCRIPTION

1. Display screen with transitional graphical user interface for the management of wine storage

1.1 : A front view of the display screen with transitional graphical user interface

1.2 : Second image thereof

1.3 : Third image thereof

1.4 : Fourth image thereof

1.5 : Fifth image thereof

1.6 : Sixth image thereof

1.7 : Seventh image thereof

The appearance of the transitional image sequentially transitions between the images shown in Reproductions 1.1-1.7. The process or period in which one image transitions to another image forms no part of the claimed design.

(Continued)

The broken lines shown in the reproductions form part of the claimed design.

1 Claim, 7 Drawing Sheets
